DUPLICATE BRIDGE BOARD OR SIMILAR ARTICLE

Dean W. Myers, Newport Beach, Calif., assignor to Frederick H. Flam, Tarzana, Calif.

Filed Mar. 29, 1965, Ser. No. 84,467

Term of patent 14 years

(Cl. D34—13)

FIGURE 1 is a perspective view of a duplicate bridge board or similar article embodying my new design;

FIG. 2 is a side elevational view thereof, taken from the side opposite that visible in FIG. 1; and

FIG. 3 is a bottom plan view thereof.

The broken-line showing of playing cards and a data card is for purposes of illustration only. The dominant features of my design reside in those portions shown in full lines.

I claim:

The ornamental design for a duplicate bridge board or similar article, substantially as shown and described.
